(57) **CLAIM**

The ornamental design for an electronic candle, as shown and described.

DESCRIPTION

FIG. 1 is an isometric view of an electronic candle with a base attached thereto.

FIG. 2 is a front view of the electronic candle of FIG. 1.

FIG. 3 is a back view of the electronic candle of FIG. 1.

FIG. 4 is a left view of the electronic candle of FIG. 1.

FIG. 5 is a top view of the electronic candle of FIG. 1.

FIG. 6 is a bottom view of the electronic candle of FIG. 1.

FIG. 7 is another isometric view of the electronic candle of FIG. 1 without the base.

FIG. 8 is a front view of the electronic candle of FIG. 7.

FIG. 9 is a back view of the electronic candle of FIG. 7.

FIG. 10 is a left view of the electronic candle of FIG. 7.

FIG. 11 is a top view of the electronic candle of FIG. 7; and,

FIG. 12 is a bottom view of the electronic candle of FIG. 7. The broken-line disclosure represents portions of the electronic candle which form no part of the claimed design.

1 Claim, 10 Drawing Sheets
